FINIAL CONSTRUCTION

Johann Martin Stangl, Flemington, N. J., assignor to Fulper Pottery Company, Flemington, N. J., a corporation of New Jersey

Application July 21, 1933, Serial No. 681,421

7 Claims. (Cl. 41—10)

My invention relates to finials and similar devices adapted to be applied to lamps and the like to secure the lamp shade on to a support therefore. My invention relates particularly to finials 5 formed of molded plastic material such as china, pottery ware, porcelain, glass, bakelite, etc.

Finials, heretofore used have ordinarily been made of metal. However, when the base of the lamp is formed from a vase or other pottery ware 10 or glass construction, the use of a finial formed of metal is objectionable as being out of harmony and failing to match the base of the lamp.

In order to overcome this objection to the use 15 of metallic finials, some finials have been made in which there is a rod extending upwardly from the threaded member which serves to secure the finial to the support for the lamp shade. Beads, ornaments and other decorative members formed 20 of glass, porcelain or the like have then been placed or assembled on the rod and held in position by an element threaded or otherwise secured to the top of the rod. Such structures necessarily have metallic pieces at both the top and bottom 25 of the finial, and if the finial is formed of transparent glass the rod extending through the ornament is clearly visible and therefore detracts from the appearance of the ornament. Furthermore, the beads or ornaments used for this purpose necessarily have a hole extending through 30 the same for applying the ornaments to the rod. This renders the ornaments weak and readily broken, and there is always danger that the beads will come loose or fall off of the rod if the element at the top thereof becomes loose or is re- 35 moved. On the other hand, if the element at the top of the rod is screwed down tight enough to hold the beads or ornaments securely, there is danger of breaking or cracking the ornaments.

I have found that very attractive finials can 40 be made in which the exposed parts of the finials are formed entirely or substantially entirely of pottery ware, china, porcelain, glass or other molded plastic materials. In some cases, structures embodying my invention may have a metallic member exposed only at the base of the finial where it is threaded on to the lamp. These structures may be formed by providing a molded 45 finial with a recess therein into which the metallic member may be inserted and secured to the body of the finial by a suitable cement.

In order to provide a satisfactory bond between 50 the molded body of the finial and the threaded member which serves to secure the finial to the support for the lamp shade, it is desirable to use 55 a cement or other agent which does not expand

so as to crack the finial and which does not contract or shrink away from the molded body of the metallic member. The cement used should dry or harden quickly and since the recess in the finial is closed and water or solvents in the cement can 5 not readily evaporate therefrom, the materials used as cements preferably should not rely upon the evaporation of water or other liquids to become hard. Cements which harden by chemical action with water are also undesirable since a 10 portion of the water may be absorbed by the pottery ware and prevented from reacting with the ingredients of the cement. I have found that those cements which are thermo-plastic are in general the most satisfactory for use in connecting the metallic member to the molded body of the finial. Typical of such thermo-plastic materials is sealing wax.

It is an object of my invention to provide an attractive and serviceable finial, the exposed portions of which are formed substantially entirely 20 of molded plastic material.

Another object of my invention is to provide a finial formed of molded plastic material having a threaded member for the attachment of the 25 finial to the lamp carried by the molded body of the finial.

A further object of my invention is to provide a finial in which there is a metallic member concealed entirely by the molded bodies of the finial. 30

Another object of my invention is to provide a finial of molded plastic material such as pottery ware having an internally threaded metallic member carried by the body of the finial and secured thereto by a cement which provides a firm 35 and permanent bond between the pottery ware and the metallic member.

Another object of my invention is to provide a finial formed of pottery ware having a metallic internally threaded member carried thereby and secured to the body of the finial by means of sealing wax. 40

These and other objects and features of my invention will appear from the following description thereof in which reference is made to the 45 accompanying figures of the drawing.

In the drawing:

Fig. 1 illustrates a finial embodying my invention having a portion thereof broken away.

Fig. 2 is an elevation of a metallic member 50 adapted for application to a finial of the type illustrated in Fig. 1.

Fig. 3 is a sectional view taken on the line 3—3 of Fig. 1.

Fig. 4 is a sectional view similar to that shown 55

in Fig. 3 illustrating an alternative form of connection between the body of the finial and the metallic member.

Fig. 5 illustrates a modified form of metallic member and finial connection, and,

Fig. 6 illustrates a further alternative form of metallic member and finial construction.

In the form of my illustration illustrated in Fig. 1 of the drawing, the body 2 of the finial is formed of a molded plastic material such as pottery ware and is provided with a recess 4 extending from the base 6 of the finial into the interior of the body. The base of the finial adjacent the opening 7 of the recess is preferably formed with 15 inturned edge or shoulder 8.

The form or design of the body 2 and the method of forming the same may be varied at will and preferably corresponds with and harmonizes in color and appearance with the design of the base 20 of the lamp to which it is to be applied.

A metallic member for securing the finial to a lamp is shown at 10 in Fig. 1, and is provided with an internally threaded recess for attaching the finial to the support for a lamp shade as in the 25 usual manner of constructing metallic or other finials. The upper portion of the metallic member is provided with an enlarged head 14 which preferably is of somewhat smaller cross section than the opening of the recess in the molded body 30 of the finial. The head 14 is connected to the base 16 of the metallic member by a neck 18 of smaller cross section than that of the head 14 so as to provide a depression into which cement for securing the metallic member to the body of the 35 finial may extend.

The cement, which preferably is sealing wax, is shown at 12 in Fig. 1. This extends beneath the shoulder at the lower side of the head 14 of the metallic member and between the head and the inturned shoulder 8 about the opening 7 of the recess.

The head 14 of the metallic member is preferably formed with a flattened side 20 or is given any irregular or non-circular surform for preventing 45 rotation of the said member with respect to the body of the finial. As shown in Fig. 2 of the drawing the metallic member used may be one of the numerous types of small brass finials commonly employed for holding small metallic lamp shades in place on the base of a lamp. However, as indicated it is preferable to flatten the side of 50 these members to prevent rotation thereof with respect to the molded body of finials embodying my invention.

As pointed out above, the cement used for securing the metallic member to the body of the finial may be of any suitable character, but it is desirable that the cement should be one which hardens quickly without the evaporation of water 55 or contact with the air to effect hardening thereof. The cement should also be one which does not expand sufficiently to crack the molded body or contract and shrink away from the molded body or metallic member. Another requirement 60 for such cements is that they shall not require too high a temperature for melting or rendering the same soft for this would also tend to crack or injure the body of the finial. The most economical and satisfactory material that I have found 65 for use as a cement and one which meets the above requirements is sealing wax. However, any other cements having the properties requisite for securing the metallic member to the body of the finial may be used if desired.

In the form of my invention illustrated in

Figs. 1, 2, and 3, both the metallic member 10 and that portion of the recess 4 adjacent the metallic member are of generally circular form. As illustrated in Fig. 4, it may be desirable in some instances to provide a metallic member 11 and 5 recess in the finial body which are square or of angular formation so that even though the metallic member should become loose within the finial body it, nevertheless, will be securely held for rotation with the body, thus enabling the 10 finial to be applied and removed from a lamp under all circumstances.

As shown in Fig. 5, the metallic member may be formed with a flange 22 adjacent the base thereof, and this flange may be located exteriorly 15 of the recess so as to prevent possible injury to the molded body of the finial upon engagement of the base of the finial with the support for the lamp shade.

In Fig. 6, I have illustrated a further alternative form of construction in which the recess in the body of the finial is provided with an inwardly projecting shoulder 24 adjacent the opening 7 of the recess. The metallic member in this construction as in that shown in Fig. 5 is provided with a flange 22 which may seat against the shoulder 24 and be located substantially entirely within the body of the finial. The metallic member thus prevents injury to the molded body of the finial even though it is invisible when 30 the finial is secured in place on the lamp.

The constructions in Figs. 5 and 6 have the further advantage that the flange 22 entirely closes the recess in the body of the finial so that the cement or sealing wax used in securing 35 the metallic member to the body of the finial is concealed from view. These constructions are particularly attractive in appearance and the possibility of using molded plastic material such as china or porcelain enables me to provide 40 finials which match or harmonize in appearance and may be of the same color and material as that of the material from which the base or other portions of the lamp are constructed. This feature has been unattainable in finials 45 heretofore employed and represents a distinct advantage in producing attractive lamps.

While I have illustrated and described certain preferred embodiments of my invention, the elements thereof may be varied considerable in form 50 and appearance and the composition of the body of the finial and the cement used for securing the metallic member thereto may also be varied as desired. It should, therefore, be understood that my invention is not limited to the particular 55 form and elements herein described except as defined by the following claims.

I claim:

1. A finial comprising a body formed of a single piece of molded composition having a recess 60 therein, a metallic member threaded internally and located within said recess with an end of the metallic member substantially flush with the base of the finial body and sealing wax within said recess engaging both said threaded member and said body for holding said threaded member in fixed position with respect to said body.

2. A finial having a body formed of pottery ware having a recess therein and a metallic member threaded internally and located wholly within said recess, said metallic member being secured to said pottery ware body by means of sealing wax.

3. A finial comprising a body formed of a 75

5 molded plastic material having a recess therein of non-circular shape, a threaded member having a portion thereof of non-circular shape, located within said recess and sealing wax between said threaded member and said body.

10 4. A finial comprising a body formed of pottery ware having a recess therein provided with an inwardly extending shoulder, an internally threaded member having a flange at the base thereof, said member being positioned within said recess with said flange engaging said shoulder and sealing wax between said member and said body.

15 5. A finial comprising a body formed of pottery ware having a recess in the base thereof, provided with an inwardly extending shoulder adjacent the opening in the body, a metallic member having an internally threaded recess and provided with a head adapted to be introduced into the recess in said body through the opening in the base thereof, said member having a neck of smaller cross section than said head between said head and the bottom of said member and sealing wax within said recess located

above the shoulder and beneath said head engaging the pottery ware and the head and neck of said metallic member.

6. A finial comprising a body formed of pottery ware having a recess in the base thereof, 5 provided with an inwardly extending shoulder adjacent the opening in the body, a metallic member having an internally threaded recess and provided with a head adapted to be introduced into the recess in said body through the opening in the base thereof, said member having a neck of smaller cross section than said head between said head and the bottom of said member and a cementing agent within said recess located above the shoulder and beneath said head 10 15 engaging the pottery ware and the neck of said metallic member.

7. A finial comprising a body formed of a single piece of molded composition, an attaching member therewithin substantially flush with the 20 surface of the body and having an external recess, and cementitious means within said recess for securing the member to the body.

J. MARTIN STANGL.
